United States Patent

Des. 237,199
Patented Oct. 14, 1975

237,199

CAPSULE

Erich W. Sauter, Cornwell Heights, Pa., assignor to Parke,
Davis & Company, Detroit, Mich.

Continuation of abandoned design applications Ser. No.
157,064, Ser. No. 157,065, and Ser. No. 157,066, all
June 25, 1971. This application July 31, 1973, Ser.
No. 384,265

Term of patent 14 years

Int. Cl. D28—01

U.S. Cl. D32—3

FIG 1

FIG 2

FIG 3

FIG 4

Fig 5

FIG. 1 is a front elevation of a capsule showing my new design;

FIG. 2 is a front elevation of a modified embodiment of the capsule illustrated in FIG. 1;

FIG. 3 is a top plan view of the capsules illustrated in FIGS. 1 and 5;

FIG. 4 is a bottom view of the capsules illustrated in FIGS. 2 and 5; and

FIG. 5 is a front elevation of a further modified embodiment of the capsule illustrated in FIG. 1.

This is a continuation of design applications Ser. Nos. D. 157,064, D. 157,065, and D. 157,066, filed June 25, 1971, and now abandoned.

I claim:
The ornamental design for a capsule, as shown and described.
